(57) **CLAIM**

The ornamental design for a suction attachment for a power tool, as shown and described.

DESCRIPTION

Cross reference is made to copending U.S. design patent application Ser. No. 29/865,622 entitled "Hammer Drill" by Vincent Hasenmayer, which was filed on even date herewith. FIG. 1 is a perspective view of a suction attachment showing my new design;

FIG. 2 is a front elevational view of the suction attachment for a power tool of FIG. 1;

FIG. 3 is a rear elevational view of the suction attachment for a power tool of FIG. 1;

FIG. 4 is a left side elevational view of the suction attachment for a power tool of FIG. 1;

FIG. 5 is a right side elevational view of the suction attachment for a power tool of FIG. 1;

FIG. 6 is a top plan view of the suction attachment for a power tool of FIG. 1; and,

FIG. 7 is a bottom plan view of the suction attachment for a power tool of FIG. 1.

The broken lines shown in the drawings depict portions of the suction attachment for a power tool that form no part of the claimed design.
